UNITED STATES PATENT OFFICE.

PHILIP A. BOWEN, OF LYNN, MASSACHUSETTS.

NAPKIN-HOLDER.

1,390,083.

Specification of Letters Patent.

Patented Sept. 6, 1921.

Application filed June 17, 1921. Serial No. 478,285.

To all whom it may concern:

Be it known that I, PHILIP A. BOWEN, a citizen of the United States, and residing at Lynn, county of Essex, State of Massachusetts, have invented an Improvement in Napkin-Holders, of which the following description, in connection with the accompanying drawing, is a specification, like characters on the drawing representing like parts.

10 This invention has for its object to provide a novel napkin holder which can be worn by a person underneath the vest or beneath the lapel of the coat and by which a napkin can be securely held.

15 My improved napkin holder is so constructed that it is concealed from view when not in use, and when in use the only part thereof which is exposed is a small retaining pin on which the napkin may be impaled.

20 The device is also constructed so that the point of the retaining pin is protected thus making it impossible for the user to injure himself on the point.

The device is of such a nature that the napkin can be readily impaled on the pin or removed therefrom, and when it is impaled on the pin it will be firmly and securely held in the desired position.

25 In order to give an understanding of the invention I have illustrated in the drawings a selected embodiment thereof which will now be described after which the novel features will be pointed out in the appended claims.

30 Figure 1 is a view showing the manner in which my improved napkin holder is used.

Fig. 2 is a vertical section through the napkin holder and the garment to which it is attached.

40 Fig. 3 is a front view of the napkin holder.

The napkin holder comprises a body member 1 having suitable means for attachment to the garment of the person using the article, and a pin-supporting member 2 pivoted to the body at 3 and having a napkin-retaining pin 4 extending therefrom. The shank of the pin 4 is curved as shown at 5 and it is provided with the point 6. The shaft of the pin is such that when the member 2 stands substantially in alinement with the body member 1 as shown in Fig. 2 the point of the pin will lie against the body member.

45 The lower portion of the pin 5, however, is separated from the body 1 a considerable distance owing to the curved shape at 5. The

body 1 is provided with an aperture 7 opposite the point 6 of the pin, said aperture being large enough to receive the point of the pin when the parts are in the position shown in Fig. 2 thereby protecting the point. A spring device is employed which normally holds the parts 1 and 2 in their alined position shown in Fig. 1 but which permits the pin-retaining member 2 to be swung about the pivot 3 thereby to separate the point of the pin from the body of the member.

50 Any suitable spring device adapted to accomplish this purpose may be employed. I have herein shown the body 1 as provided with slits 8 forming between them a spring finger 9, the end of which normally rests against a shoulder 10 formed on the member 2. When the member 2 is turned into the dotted line position the shoulder 10 acts against the finger 9 and flexes the latter as shown in dotted lines Fig. 2 the resiliency of the finger acting to return the parts to the full line position when the member 2 is released.

55 Any suitable means may be employed for attaching the device to the garment. I have herein shown the member 1 as provided at its upper end with a clasp pin 11 for this purpose.

60 The device may be worn on the inside of the vest, on the inside of the coat or on the inside of the lapel of the coat as desired. I have shown it in the drawing as worn on the inside of the vest 12.

65 In securing the device in position the clasp pin 11 will be caught into the vest on the inside thereof so that the body will hang down on the interior of the vest. The member 2 is then swung into the dotted line position Fig. 2 thus bringing the pin 4 into a horizontal position, and when in this position the pin is inserted through the vest and the member 2 is then released. The spring finger 9 carries the pin 4 into the full line position Fig. 2 so that it overlies the outside of the vest and the pressure against the point of the pin will cause the material of the vest to be crowded into the aperture 7 somewhat as shown in Fig. 2. The point of the pin thus becomes protected by the material of the vest so that there is no danger that the wearer will prick himself on the pin.

70 When the device is in this position the only exposed portion thereof is the pin 4 which is very inconspicuous.

To attach a napkin to the napkin holder the operator will press backwardly on the member 2 slightly thus separating the point of the pin from the vest and then the napkin 13 may be impaled on the pin as shown in Fig. 1 and in dotted lines Fig. 2. When the member 2 is released after the napkin has been applied to the pin the spring 9 will return the point of the pin into its protected position. The napkin can be removed by simply raising it off the pin.

When the device is not to be used for holding a napkin it may be left in the position shown in Fig. 2 or if desired the pin 4 may be withdrawn from the vest so that the entire device will be situated inside of the vest or of the garment.

It is my intention that the device should be worn continually on the garment and then brought into use at meal time or whenever it is desirable to use a napkin. If a person prefers, however, he may detach the article from his clothing after each meal, although it is not necessary as the device is entirely out of the way when not in use and the point of the pin is normally protected so that it can cause no injury to a person's hands or to the clothing.

I claim.

30 1. A napkin holder comprising a body member adapted to be attached to a garment on the inside thereof, a pin-supporting member pivoted to the body member, a napkin-

holding pin secured to the pin-supporting member and adapted to be inserted through 35 the garment and placed in position to support a napkin by the swinging movement of the said pin-supporting member.

2. A napkin holder comprising a body member adapted to be attached to a garment 40 on the inside thereof, a pin-supporting member pivoted to the body member, a napkin-holding pin secured to the pin-supporting member and adapted to be inserted through the garment and placed in position to sup- 45 port a napkin by the swinging movement of the pin-supporting member, said body member having an aperture to receive the point of the pin thereby to protect the latter.

3. A napkin holder comprising a body 50 member adapted to be attached to a garment on the inside thereof, a pin-supporting member pivoted to the body member, a napkin-holding pin secured to the pin-supporting member and adapted to be inserted through 55 the garment and placed in position to support a napkin by the swinging movement of the pin-supporting member, said body member having an aperture to receive the point of the pin thereby to protect the latter, and 60 a spring acting on the pin-supporting member and yieldingly holding the pin in its operative position with its pin protected.

In testimony whereof, I have signed my name to this specification.

PHILIP A. BOWEN.
